UNITED STATES PATENT OFFICE.

EDWARD W. SALMON, JR., OF BALTIMORE, MARYLAND, ASSIGNEE, BY MESNE ASSIGNMENTS, TO AMERICAN FILM-SAFE CORPORATION, A CORPORATION OF MARYLAND.

FILM-STORAGE CABINET.

Application filed May 31, 1918, Serial No. 237,551. Renewed August 7, 1924.

To all whom it may concern:

Be it known that I, EDWARD W. SALMON, Jr., citizen of the United States of America, residing at Baltimore, State of Maryland, have invented certain new and useful Improvements in Film-Storage Cabinets, of which the following is a specification.

The invention relates to a film storage cabinet.

10 The object of the present invention is to improve the construction of film storage cabinets more specially the means for holding the film spools and to provide a simple, practical and efficient film storage cabinet 15 provided with a swinging door and equipped with means connected with and operated by the door for holding the film spool to withdraw the same from the compartment when the door is opened and to carry the film 20 holding means into the compartment when the door is closed.

25 A further object of the invention is to provide a construction of this character and capable, at the same time, of enabling a 30 compartment to be used having a height only slightly in excess of the diameter of the film spool whereby a minimum sized compartment may be employed and a compact arrangement of the film obtained.

35 Another object of the invention resides in a film or other filing cabinet, embodying among other characteristics, a cabinet in which is mounted a record holder having connection with the door so that when the 40 door is opened the holder is given a compound movement from normal position through the door opening, the connection between the door and the holder causing the holder to travel forwardly and in its travel roll forwardly through the door opening to permit ready access to the record in the holder.

45 Another object is to provide a film or other record cabinet in which a record holder is mounted to normally gravitate to position within the cabinet and which has connection with the door of the cabinet so that it can be moved forwardly through the 50 door opening when the door is opened against its gravitating characteristics so that upon release of the door the gravitating movement of the holder will effect an automatic closing of the door.

55 One object of the invention is to provide

a cabinet for the filing and storage of motion picture films or the like provided with a closure and equipped with means for the reception and support of the films or the like and which is swingingly mounted and which has connection with the closure so as to be shifted forwardly when the closure is opened and the holder, by virtue of its mounting and connection with the door, being adapted to pull the closure to closed position when the operator releases the closure.

65 A still further object of the invention resides in the provision of a film cabinet which is constructed of fire proof material and in which the door of the cabinet may be locked without danger of explosion in the cabinet incident to fire, there being means provided to operate automatically in the event of fire to permit the free and ready escape of gases and fumes from the cabinet.

75 With the above and other objects in view, the present invention consists in the combination and arrangement of parts hereinafter more fully described, illustrated in the accompanying drawings, and particularly 80 pointed out in the appended claims, it being understood that changes may be made in the form, size, proportion and minor details without departing from the spirit or sacrificing any of the advantages of the invention.

85 In the drawings:

Figure 1 is a perspective view of a portion of a film storage cabinet constructed in accordance with this invention, one of the doors being open;

Fig. 2 is a vertical sectional view taken longitudinally of the compartment;

Fig. 3 is a transverse sectional view of one of the compartments and the film spool carrying device;

Figs. 4 and 5 are detail views illustrating the construction of the jamb frame.

90 In the accompanying drawings, in which is illustrated one embodiment of the invention, the film spool or record carrying device comprises in its construction a holder 1 constructed of suitable material preferably metal and composed of spaced sides 2 and a curved peripheral connecting portion 105 3 connecting the sides at the front, rear and bottom edges thereof. The holder is open at the top to enable a film spool or other record 4 to be readily placed therein and removed therefrom when the door 5 of the 110

compartment 6 of the film storage cabinet 7 is open, as illustrated in Fig. 1 of the drawings.

The holder 1 has a floating action and 5 to effect this floating action, the holder is supported by crossed, oppositely inclined links 8 and 9 which are substantially oblong. The front link 8 is inclined upwardly and rearwardly and is composed of spaced sides 10 and a connecting transverse front pivot portion 10 being pivoted at the front of the base plate 11. The rear or upper terminals 12 of the sides of the link 8 are bent inwardly to form pivots, which are arranged in a 15 suitable bearing 13 located at the back of the holder below the horizontal plane of the center of the same when the door is closed as clearly shown in Fig. 2 of the drawings. It will be noted that the link 8 is of greater 20 length than the link 9, for a purpose presently explained.

The base plate 11 is constructed of metal or other suitable material and it is provided with side flanges 14 and with front and rear 25 bearings 15 and 16 for the reception of the pivot 10 of the link 8 and the pivot 17 of the link 9. The rear link 9, which is composed of spaced sides and the transverse pivot portion 17, extends upwardly and forwardly 30 from the rear bearing 16 to the front portion of the holder 1 and its upper or front terminals 18 are bent inwardly at right angles to form pivots mounted in suitable bearings 19 at the front of the holder 1 and 35 at a point below the horizontal plane of the center of the holder when the door is closed.

By the above mentioned arrangement of links, the holder is mounted for a floating movement and when it is drawn forwardly 40 by the downward swinging of the door 5 it is partially rotated or rolled as it floats through the door opening. This is accomplished through the operation of the crossed links 8 and 9 to carry its open top to the 45 front and arrange the open top of the holder at an inclination at the open front of the compartment to afford ready access to the film spool or other record and enable the same to be easily placed in and removed 50 from the holder.

The holder is connected with the door by a substantially oblong link 20 composed of spaced sides and front and rear connecting portions 21 and 22, the front connecting portion 55 being mounted in a suitable bearing 23 of the door and the rear connecting portion 22 being arranged in a suitable bearing 24 at the back of the holder. The transverse portions 21 and 22 form pivots and the connecting link 20 is arranged at a slight inclination and extends upwardly and rearwardly 60 from the lower portion of the door when the latter is closed and in this position of the door and the holder the link 20 is located below the horizontal plane of the 65

center of the holder. The upper rear end of the connecting link is connected with the holder at the back thereof adjacent to the upper edges of the same and the open top of the holder is disposed at a slight rearward inclination when the door is closed. The holder is provided at its open top portion 70 with flanges which extend laterally outwardly from the sides 2, as indicated at α for the purpose of engaging the sides of the link 20 when the door 5 is opened to a certain degree and thereby arrest the outward swing of the door and also arrest the forward movement of the holder at a point short of dead center. By thus limiting the outward 75 movement of the door and holder, and the holder having a rolling motion upwardly to a point short of dead center it will be clear that immediately upon release of the door by the operator, the holder will gravitate 80 downwardly and simultaneously close the door tightly. When the door moves to its closed position it is automatically locked by the pivoted latches 27 located at the top of the compartment, the door being preferably 85 hinged mounted at the bottom of the compartment as indicated at 25'.

The automatic closing action of the door 90 through the operation of the film spool or other record holder carrying mechanism 95 may be increased by providing the rear portion of the holder with a suitable weight 25 which may be of any desired size and which may also be secured to the back of the holder in any suitable manner. The weight 25 100 may be eliminated, in view of the particular form of supporting means for the holder, and if used at all, it is for the purpose of increasing the gravitating movement of the holder. 105

The rotary and backward and forward movement of the holder enables the same to be withdrawn from the compartment by the outward and downward swinging of the door with but little upward movement of 110 the holder and it is not necessary to materially increase the height of the compartment which is only slightly in excess of the diameter of the record. Also by partially rotating the holder to turn the open top to 115 the front when the door is opened it is unnecessary to entirely withdraw the holder from the compartment and the forward and backward movement of the holder is thereby reduced to a minimum. 120

The movement of the holder is comparatively noiseless and without friction and while the holder is shown operatively connected with a downwardly swinging door, any other suitable operating means may be 125 employed and it can be pulled out by hand without separate operating means. Moreover, the degree of backward and forward and rotary or rolling movement may be controlled by varying the length of the links 130

and their pivotal points. Furthermore, the holder may be varied in form and with the crossed links may be employed for a variety of purposes where the keeping of records is 5 essential.

As shown in the accompanying drawings the holder rests normally in an inclined position rearwardly of the cabinet and off center as distinguished from a perfectly horizontal mounting. In other words, by virtue 10 of the arrangement of long and short links 8 and 9, the particular holder illustrated is caused to assume normally such a position as to throw the open side of the holder rearwardly, the short and long links coacting to provide for the upward rolling movement of the holder when the latter is pulled upon by the connection therebetween and the door.

Thus it will be seen that the holder does 20 not merely rock or swing from side to side, but that it has a compound movement, that is to say, while it is moving forwardly it is rolling or given a progressive partial rotative movement.

In the event of a fire in this compartment, incident to the film therein catching fire, it is not necessary to unlatch the door to permit the escape of fumes and gases in order to 25 avoid an explosion. My invention is such that explosions in the cabinet cannot occur 30 and smoke and fumes cannot enter the room in which the cabinet is located as would be the case if the door be opened in the event of a fire. As shown, all gases and fumes in 35 the cabinet, in the event of a fire therein, will by expansion, operate and open the normally closed valve 28 to permit the escape of the fumes and gases to the atmosphere as clearly set forth in my companion application filed on even date herewith.

It will be understood from the foregoing that while the present invention is designed particularly for the storing of motion picture films that it is readily applicable for 40 other filing purposes. Among the main objects involved in the present invention with respect to structural characteristics, it may be noted that the holder is supported in unstable equilibrium, that is to say, that the 45 holder is supported out of contact with the walls of the cabinet and has an easy free and flexible mounting as compared with a rigid pivotal mounting. This particular 50 type of supporting means is such as to require a pulling or a forcing action on the holder to unseat it from its position into which it normally gravitates. When the 55 door of the cabinet which has connection with the holder is opened, the holder is pulled upon to move forwardly toward and through the door opening and in this travel the supporting means is actuated to raise and lower or partially rotate the holder so 60 that there is a compound action given the holder in its travel from its rearward to its

forward position, the compound action being manifest on the return movement by gravity of the holder except that the action is reversed. The fact is the holder is supported at all times in constant unstable equilibrium because the moment the door is released, the holder actuates the supporting means and also the door to effect automatic closing of the door to insure the cabinet being open only when access is desired to the 75 holder or a record confined therein.

What I claim is:

1. The combination of a cabinet provided with a hinged door, a holder in the cabinet, means for movably supporting the holder in 80 the cabinet, a connection between the door and the holder to pull upon the holder to cause it to travel forwardly through the door opening when the door is opened and simultaneously actuate the movable supporting 85 means to impart an upwardly inclined rolling motion to the holder throughout its travel, and means to provide an engagement between the holder and the said connection between the door and the holder to arrest 90 the travel of the holder and limit the outward movement of the door prior to travel of the holder past dead center whereby to permit automatic return movement of the holder and door upon release of the door. 95

2. The combination of a cabinet provided with a hinged door, a holder in the cabinet, the holder having a lateral projection, means for swingingly supporting the holder in the cabinet, a connection between the door and the holder to pull upon the holder and cause it to travel forwardly through the door opening when the door is opened and simultaneously actuate the swinging supporting means to impart a rolling motion to the holder throughout its travel, the forward travel of the holder being limited at a point short of dead center of movement of the holder by 100 said projection contacting with the connection between the door and the holder. 105

3. The combination of a cabinet provided with a hinged door, a holder in the cabinet, means for movably supporting the holder in the cabinet, a connection between the door and the holder to cause the holder to travel forwardly through the door opening when the door is opened and simultaneously actuate the movable supporting means to impart a rolling motion to the holder throughout its travel, and means whereby to arrest the dual 110 forward and rolling movements of the holder short of dead center. 115

4. The combination of a cabinet provided with a hinged door, a holder in the cabinet, means for floatingly supporting the holder in the cabinet, a connection between the door and the holder to cause the holder to travel forwardly through the door opening when the door is opened and to simultaneously 120 actuate the said supporting means to impart a 125

rolling motion to the holder throughout its forward travel, and means whereby to limit the outward swing of the door prior to the passage of the holder in its travel to dead center and thereby permit of an automatic return of the door and holder to normal positions.

5. The combination of a cabinet provided with a door, a holder movable into and out 10 of the cabinet, and supporting means for the holder comprising connecting members of unequal length connecting the holder with the cabinet, and a connection between the door and the holder to cause the holder to 15 move upwardly and at the same time partially rotate when the door is opened, whereby the holder is supported in constant unstable equilibrium to exert a constant closing pull on the door at all times, one of said 20 members being arranged to engage the holder at one position of movement of the latter to limit the opening movement of the door.

6. The combination of a cabinet, a door 25 hingedly connected with the cabinet, a holder in the cabinet, and connections between the holder and the door and the cabinet to support the holder for a floating movement whereby upon opening the door the holder is 30 raised to a point above its normal position in the cabinet and caused to float and roll in an inclined direction from its raising point forwardly through the door opening.

7. The combination of a cabinet, a door 35 hingedly connected to the cabinet, a holder in the cabinet, and means connecting the holder and the door and the cabinet and operable upon outward swing of the door to simultaneously raise the holder to a point 40 above its normal position in the cabinet and cause the same to move upwardly from its raising point forwardly to project the same through the door opening when the door is opened, the upper edge of the holder lying 45 parallel with and engaging the connecting means between the door and the holder at the limit of outward movement of the door so as to limit the outward movement of the holder to a point short of dead center whereby upon the release of the door the holder 50 gravitates to its normal position in the cabinet and automatically closes the door.

8. The combination of a cabinet provided 55 with a door, a holder, a connection between the door and the holder whereby to pull the holder through the door opening when the door is opened, means for the support of the holder which is actuated by the holder under the influence of said pulling action 60 to give the holder a partial rotative movement independently of the pulling action and simultaneously therewith, and means whereby the partial rotative movement of the holder is arrested at a point short of

dead center so as to provide for an automatic 65 closing of the door.

9. The combination of a cabinet provided with a door, a holder in the cabinet, oppositely arranged diagonally disposed links 70 pivotally connected to the bottom of the cabinet and pivotally connected to opposite ends of the holder, one of the links being shorter than the other, and a link connection between the door and the holder whereby upon opening the door the holder 75 is given a rotative movement through the door opening.

10. The combination of a cabinet provided with a door, a holder in the cabinet, oppositely arranged diagonally disposed 80 links pivotally connected to the bottom of the cabinet and pivotally connected to opposite ends of the holder, one of the links being shorter than the other, and a link connection between the door and the holder 85 whereby upon opening the door the holder is given an upward rotative movement through the door opening, and means for engagement with said connection between the door and holder to limit the outward 90 movement of the holder short of dead center so as to effect a gravitating return movement of the holder upon release of the door and a simultaneous closing of the door.

11. The combination of a cabinet having 95 a hinged door, a holder in the cabinet, a plurality of members connecting the holder with the cabinet and the door whereby to impart a continuous, forward, bodily, rolling motion to the holder when the door is 100 opened, and means for limiting the forward movement of the holder short of dead center so that upon release of the opened door the holder will gravitate into the cabinet and thereby automatically close the door.

12. The combination of a compartment having a door opening, a hinged door for the opening, a base plate mounted upon the bottom of the compartment and provided with parallel upstanding ribs, crossed, U-shaped links swingingly seated on said ribs, a holder pivoted to said links and supported thereby within the links above the base plate, and a combination between the holder and the door whereby upon opening the door the U-shaped links are 110 swung forwardly and the holder swung bodily upwardly and forwardly to permit insertion or removal of records from the holder through the door opening.

13. The combination of a compartment having a door opening, a hinged door for the opening, a base plate mounted upon the bottom of the compartment and provided with upstanding ribs, crossed, U-shaped links swingingly seated on said ribs, a holder pivoted to said links and supported thereby within the links above the base 125

- plate, and a connection between the holder and the door whereby upon opening the door the U-shaped links are swung forwardly and the holder swung upwardly and forwardly to permit insertion or removal of records from the holder through the door opening, said links limiting outward movement of the door and holder short of dead center whereby upon release of the door, the door closes automatically under the influence of the holder. 14. The combination of a cabinet provided with a door, a holder in the cabinet, a base plate on the bottom of the cabinet, having spaced longitudinally disposed upstanding ribs, oppositely arranged diagonally disposed supporting elements pivotally connected to the ribs and pivotally connected to opposite ends of the holder, one of the supporting elements being shorter than the other, whereby upon releasing the holder, after an outward pull thereon, the holder normally moves rearwardly to its position over the base. 15. A holder for filing and storing records comprising a base provided with spaced, parallel upstanding ribs, the ribs having seats therein located above the base, a holder disposed over the base, oppositely arranged diagonally disposed supporting elements pivotally connected to the ribs and pivotally connected to opposite ends of the holder, one of the supporting elements being shorter than the other, whereby upon releasing the holder, after an outward pull thereon, the holder normally moves rearwardly to its position over the base. 16. The combination of a cabinet having a hinged door, a holder in the cabinet, oppositely arranged diagonally disposed links pivotally mounted upon the bottom of the cabinet and pivotally connected to opposite ends of the holder, one of the links being shorter than the other, and a link connection between the door and the holder whereby upon opening the door the holder is moved forwardly through the door opening and whereby upon release of the opened door the holder pulls the door to closed position. 17. In testimony whereof I affix my signature.

EDWARD W. SALMON, JR.
